(57) **CLAIM**

The ornamental design for a golf cart turn signal switch, as shown and described.

DESCRIPTION

FIG. 1 is a perspective view of a golf cart turn signal switch showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are included for illustrating unclaimed portions of the golf cart turn signal switch and form no part of the claimed design.
